Primary Examiner — Darlington Ly

CLAIM

The ornamental design for a bike rack for vehicle as shown and described.

DESCRIPTION

1. Bike rack for vehicle

1.1 is a perspective view of a bike rack for vehicle embodying my new design;

1.2 is a front elevation view thereof;

1.3 is a rear elevation view thereof;

1.4 is a top plan view thereof;

1.5 is a bottom plan view thereof;

1.6 is a left side elevation view thereof; and

1.7 is a right side elevation view thereof.

Used to install bicycles on bicycle stands at the rear of the vehicle.

The broken lines in the drawings depict portions of the bike rack for vehicle that form no part of the claimed design.

1 Claim, 7 Drawing Sheets
